(57) CLAIM

The ornamental design for a portion of a shoe upper, as shown and described.

DESCRIPTION

FIG. 1 is a perspective view of a portion of a shoe upper according to my new design;

FIG. 2 is an enlarged perspective view thereof;

FIG. 3 is an enlarged top plan view thereof; and,

FIG. 4 is an enlarged cross-section view thereof.

The broken lines shown herein for illustrative purposes of the environment or which define the bounds of the claimed design form no part of the claimed design.

1 Claim, 3 Drawing Sheets

FIG. 1

FIG. 4
